UNITED STATES PATENT OFFICE.

HENRY C. BUNTING, OF DUNBAR, PENNSYLVANIA.

LEVELING DEVICE.

No. 866,429.

Specification of Letters Patent.

Patented Sept. 17, 1907.

Application filed November 10, 1906. Serial No. 342,872.

To all whom it may concern:

Be it known that I, HENRY C. BUNTING, a citizen of the United States, residing at Dunbar, in the county of Fayette and State of Pennsylvania, have invented new 5 and useful Improvements in Leveling Devices, of which the following is a specification.

This invention relates to leveling devices designed especially for application to radiator feet for holding the radiator plumb on an inclined surface, and has for 10 its objects to provide a comparatively simple, inexpensive device of this character which may be readily applied for use, and one which may be conveniently adjusted in the operation of leveling the radiator.

With these and other objects in view, the invention 15 comprises the novel features of construction and combination of parts more fully hereinafter described.

In the accompanying drawings: Figure 1 is an elevation of a radiator equipped with leveling devices embodying the invention. Fig. 2 is a sectional view 20 taken centrally and longitudinally through one of the leveling devices. Fig. 3 is an end view of the device.

Referring to the drawings, 1 designates a radiator or other body having feet 2 to which are applied leveling devices 3 adapted to rest on the floor surface 4; these 25 parts with the exception of the devices 3, being of usual form and material.

The leveling devices 3* constituting the subject-matter of the invention each comprise a tubular body portion 5 consisting of a length of pipe tubing inter- 30 nally threaded at 6 throughout its entire length, and a movable disk-like member 7 marginally threaded for engagement with the threads 6 for adjustment longitudinally of the body 5, there being formed at the center

of the adjustable member or disk 7 a square or other non-circular tool receiving opening 8 formed wholly 35 through the disk to open at both sides thereof.

In practice, and in setting up the radiator, the leveling devices 3 are arranged under one or more of the legs 2 in accord with the unevenness of the floor surface, it being observed, as shown in Fig. 2, that the body portion 40 5 of the device is of such diameter that the leg 2 will seat loosely therein and rest upon and be sustained wholly by the adjustable bearing member 7 which may be moved upward or downward as the case may be in the operation of leveling the radiator by introducing a 45 tool into the opening 8 for rotating the member.

It is to be particularly observed that the device is owing to its simplicity susceptible of ready adjustment, and furthermore, that inasmuch as the opening 8 extends wholly through the bearing member 7 the leveling device as a whole may be arranged with either end 50 uppermost, thus facilitating the operation of applying the devices and overcoming the necessity for observing especial care in the arrangement of the parts.

Having thus described my invention, what I claim is: 55

A leveling device comprising a hollow, internally screw-threaded cylinder open at both ends, and a marginally screw-threaded disk having its threaded portion in adjustable engagement with the threaded portion of the cylinder, said disk having its axial dimension substantially 60 less than the length of the cylinder, and being provided with a centrally located non-circular opening.

In testimony whereof, I affix my signature in presence of two witnesses.

HENRY C. BUNTING.
